UNITED STATES PATENT OFFICE.

OTTO SCHWENCK, OF RICHMOND, VIRGINIA, ASSIGNOR TO BRITISH-AMERICAN TOBACCO COMPANY, LIMITED, OF LONDON, ENGLAND, A CORPORATION OF GREAT BRITAIN.

CARTON-HINGING MACHINE.

Application filed March 13, 1924. Serial No. 698,988.

This invention relates to a carton hinging machine particularly adapted to apply hinges of flexible material, such as tough paper, muslin or the like, to cartons constructed of heavy paste-board, or similar material, and containing a large number of boxes, pouches, or packages of cigarettes, or of similar commodities. In packing cigarettes for the market, groups, usually of 10 or 20, are packed, either in tin or card-board "boxes", or in paper "pouches" which are open at one end, or in paper "packages" which are closed at both ends. These boxes, or pouches, or packages, as the case may be, are then packed in "cartons" constructed of heavy paste-board having covers or lids of the same material, and also having "hinges" of tough paper. The cartons are then packed in "cases" of still heavier material, for shipment. The term "cartons", as used herein, has the special meaning which is of necessity associated with it in the industry, in order to avoid constant confusion of the name of the different cigarette containers used. Such cartons go through the machine loaded with cigarette boxes, pouches or packages; and a hinge is automatically applied to each carton and lid in transit.

Heretofore, so far as I am aware, such hinges have been applied to such cartons by means of manual labor. The main object of the present invention is the production of a machine to automatically apply flexible hinges to cartons of the kind mentioned. Another object of the invention is the production of such a machine which applies the hinges not only to the exterior of the cartons, but also to their interior, thus forming a double hinge. With these and other objects not specifically mentioned in view, the invention consists in certain constructions and combinations which will be herein-after fully described and then specifically set forth in the claims hereunto appended.

In the accompanying drawings, which form a part of this specification and in which like characters of reference indicate the same or like parts, Figs. 1, 1^a, 1^b and 1^c, taken together, illustrate a front elevation, partly in section, of a machine constructed in accordance with the invention. Figs. 2,

2^a, 2^b, and 2^c, taken together, illustrate a plan view of the structure shown in Figs. 1, 1^a, 1^b and 1^c. Fig. 3 is a plan view, on an enlarged scale, of one of the hinge carriers and of a source of hinge supply in connection with which the carrier operates. Fig. 4 is a cross-sectional view taken on the line 4—4 in Fig. 1^a. Fig. 5 is a cross-sectional view, on an enlarged scale, taken on the line 5—5 in Fig. 4. Fig. 6 is a cross-sectional view taken on the line 6—6 in Fig. 5. Fig. 7 is a cross-sectional view taken on the line 7—7 in Fig. 1^a. Fig. 8 is a cross-sectional view taken on the line 8—8 in Fig. 1^b. Fig. 9 is a cross-sectional view taken on the line 9—9 in Fig. 1^c. Fig. 10 is a detail view, on an enlarged scale, of the main driving gear of the machine. Fig. 11 is a longitudinal section view taken on the line 11—11 in Fig. 2^c. Fig. 12 is a sectional plan view taken on the line 12—12 in Fig. 11. And Fig. 13 is an end elevation of the carton closing mechanism.

In carrying the invention into effect, there is provided a source of carton supply, a source of hinge supply, and means for successively assembling cartons and hinges drawn from said sources. In the best constructions, the assembling means includes a mechanism for successively forwarding the cartons from the source of carton supply to the assembling position; mechanism for forwarding hinges from the source of hinge supply to the assembling position; mechanism for supplying adhesive to the hinges; mechanism for pressing the adhesive hinges against the cartons; mechanism for applying heat to the cartons and hinges at their junction to dry the adhesive; mechanism for opening each carton after a hinge has been applied to its exterior, in order that a hinge may be thereafter applied to its interior; and mechanism for closing each carton after a hinge has been applied to its interior. The above mentioned sources, means and mechanisms may be widely varied in construction within the scope of the claims, for the particular device selected to illustrate the invention is but one of many possible concrete embodiments of the same. The invention, therefore, is not to be re-

stricted to the precise details of the structure shown and described. Furthermore, certain parts of the machine are capable of use independent of other parts, and such independent use is contemplated.

The invention contemplates the use of a source of carton supply including mechanism for so supporting a stack of cartons that they may be successively removed from the bottom of the stack. As shown, this mechanism includes a bottomless magazine consisting of flat uprights 14-15 and angular uprights 16-17, all supported on a bracket 18, bolted to the end of a bed plate 19, which is the main bed plate of the machine. The uprights of the magazine are held in proper spaced relation by means of straps 20-21, riveted or otherwise secured thereto; and the whole magazine structure leans a little in the direction in which cartons are removed therefrom. Resting upon the upper surface of the bracket 18 below the bottom of the magazine are two wooden blocks 22, one at either side of the magazine; and just above the front block 22 there is hinged to the corner of the magazine a spring-pressed gate 23. The blocks 22, the angular upright 17, and the gate 23 coact to properly locate the lowermost carton of the stack in the magazine, so that it will be properly engaged by forwarding mechanism which takes it from the bottom of the magazine and transfers it to assembling position, and thence out of the machine. The tension of the torsion spring 24 of the gate 23 is sufficient to hold the lowermost carton within the confines of the magazine against accidental displacement until the proper time arrives to remove the carton from the magazine. When that occurs, the gate 23 swings open, permits the carton to pass; and after the carton has passed, it swings back to its normal position, as shown in Fig. 2.

It is necessary to support all of the cartons in the stack while the bottommost carton is being removed therefrom, and this is effected by detent devices 25-25, fulcrumed on studs 26-26, secured in the bracket 18 before referred to. The detent devices 25-25 are further provided with inwardly extending arms 27-27, each carrying a roller 28. Each of the detent devices is further provided with a short lug 29 normally contacting with an adjusting screw 30, threaded in a bearing carried by the bracket 18. The two detent devices are connected by means of a tension spring 31 which normally operates to hold the lugs 29 against the adjusting screws 30, and thus maintain the free ends of the detent devices in their proper position between the lowermost carton and the one immediately above it.

For the purpose of forwarding cartons from the magazine or other source of car-

ton supply to assembling position, there is provided a conveyor having carton engaging devices which successively come in contact with cartons in the source of supply and force them out therefrom. As shown, this conveyor includes a chain 32 provided with a series of carton engaging devices or lugs 33. In Figs. 1 and 2, the upper run of the chain 32 moves toward the right, and the lugs 33 are so spaced with relation to the arms 27 that one of said lugs comes in contact with the rollers 28-28 immediately after the lowermost carton of the stack in the magazine has been removed therefrom. As the lug 33 moves forward, the detent devices 25-25 are swung outwardly on their fulcrums until they are clear of the then lowermost carton of the stack. The whole stack then drops until the lowermost carton rests on the blocks 22-22. As soon as the stack has dropped, the lug 33 passes out of engagement with the rollers 28-28, and the spring 31 causes the detent devices to again come into position between the lowermost carton and the one immediately above it, in readiness to support the stack during the next carton removing operation.

As the lugs 33 successively push the cartons from the bottom of the stack in the magazine, they move them into a horizontal pathway extending along the machine. This pathway is provided with a double series of large carton engaging and supporting rollers 34. The pathway is further provided with a series of smaller rollers 35 carried in a frame 36 mounted on the bed plate 19. It may be here remarked that in the use of the machine shown for hinging cigarette cartons, the cartons come to the machine loaded with packages and with the lid in place on the body of the carton. The purpose of the upper rollers 35 is to hold this lid in place as the carton is forwarded by the chain 32 and lugs 33.

The forwarding means or chain is given an intermittent or step-by-step movement in order to successively move the cartons from the magazine to a position where a hinge is applied exteriorly thereto; thence to a position where the lid is opened; thence to a position where a hinge is applied interiorly to the carton; thence to a position where the lid is again closed; and thence out of the machine. The chain runs idly over a sprocket 37 adjacent the magazine; it also runs over and is driven by a sprocket 38 at the other end of the machine and fast on a shaft 39 (see Figs. 1, 11 and 12). The shaft 39 is journaled in suitable bearings in the frame of the machine, and it carries a pinion 40 in mesh with a gear 41 which is loosely mounted on a stud 42 secured in the machine frame by means of a nut 43. Screwed to the gear 41 at 43 is a 4-slot Geneva stop-plate 44. This Geneva stop-plate is alternately

engaged by two rollers 45 carried at opposite ends of a lever 46 fulcrumed on a stud 47 secured in the machine frame by means of a nut 48. Fast to the hub of the lever 46 is a sprocket 49 over which runs a chain 50 which drives the said sprocket. Also fast on the hub of the lever 46 is an adjustable cam 51 which is in constant engagement with a cam bowl 52 formed on one end of a lever 10 53 which is fulcrumed on the stud 47 before referred to. The opposite end of the lever 53 has a lug 54 acting as a locking pawl in conjunction with an adjustable plate 55 having locking notches 56 in its periphery. 15 This plate is fast on the pinion 40 before referred to. The function of the lug 54 is to lock the forwarding chain against accidental displacement while a series of cartons is in position and being acted upon at 20 the several stations at which they stop on their travel through the machine.

The chain 50 runs over and derives its motion from a sprocket 57 (see Fig. 7) fast on one end of a shaft 58 journaled in a suitable bearing in a bracket 59 depending from the bed plate 19. The other end of the shaft 58 carries a bevel gear 60 which is in mesh with and driven by a second bevel gear 61 fast on a shaft 62 journaled in suitable bearings in the frame of the machine. Near the right end of the machine, the shaft 62 carries a slip clutch gear 63 which is in mesh with and driven by a pinion 64 formed on the end of a short shaft extending out beyond the machine frame and carrying on its projecting end a fast and loose pulley 65 and 66. The belt shifting device 67 is provided for shifting the driving belt 68 in a well known manner. By means of the structure 40 so far described, the cartons are successively moved from position of rest to position of rest in their travel through the machine.

After leaving the magazine a carton comes 45 to rest first in position to be assembled with a hinge, with the latter applied exteriorly to the carton. A source of hinge supply is located adjacent this assembling position and, as shown, it includes an inclined bottomless magazine 69 supported by brackets 70 and 71 rising from the bed plate 19. In the machine shown, the hinges are strips of tough paper, and a stack of them rests on the inclined surface of the magazine with 55 the lower end of the stack under two spring fingers 72-73 and engaged by knife-edged detents 74 of well known construction and operation. Ordinarily a block or weight, not shown, is placed in the magazine above the hinges in order to move the stack down to the detents 74 as the hinges are successively removed from the magazine. Referring particularly to Fig. 4, CB indicates a carton body resting on one of the rollers 34 of the 60 pathway before referred to, and CL indi- cates the lid of the carton in position on the body. It will be noticed that the outer peripheral surface of the lid is offset from the outer surface of the body of the carton. This obviously adds to the difficulty of applying a hinge both to the lid and the body of the carton. While the carton is being forwarded to its new position, a hinge is being removed from the hinge magazine by suitable mechanism and forwarded to this position, which is the assembling position for the carton and hinge. In the machine shown, adhesive is applied to the hinge in transit from the magazine to the assembling position, and for this purpose there is provided an adhesive fountain 75 supported by the brackets 70 and 71 before referred to. Working in this fountain is an adhesive distributing roller 76, and an adhesive applying roller 77 which takes adhesive from the distributing roller and rolls it on a hinge as the latter is caused to pass said applying roller at equal surface speed therewith. The distributing roller 76 is rotated by a gear 78 on its shaft, which in turn is rotated by a pinion 79 on the shaft 80 of the applying roller. The other end of the shaft 80 carries a gear 81 which is in mesh with and driven by a gear 82 fast on one end of a short shaft journaled in the bracket 70 and carrying a sprocket 83 over which runs a driving chain 84 which derives its motion from a shaft 85 journaled in suitable bearings in the main frame of the machine below the bed plate 19. The shaft 85 derives its motion from the main power shaft 62 through the agency of a sprocket and chain connection 86. 100

In the machine shown, the mechanism for forwarding hinges from the source of hinge supply to assembling position includes a suction hinge carrier and operating connections. This suction hinge carrier is in the form of a hollow rectangular perforated head 87 which is mounted on one end of a tube 88, slidably mounted in bearings 89 and 90 formed on a bracket 91, the latter being fast on a short shaft 92 journaled in a bracket 93 rising from the bed plate 19 before referred to. To the far end of the shaft 92 is clamped an arm 94, and the free end of this arm is pivotally connected to one end of a connecting rod 95, the other end of this rod being connected to the free end of a cam lever 96 fulcrumed at 97 to a bracket 98 secured to the side of the bed plate 19 before referred to. The cam lever 96 carries a cam bowl indicated at 99 which tracks in a suitable groove in a cam indicated at 100 in Fig. 1, and carried by the main shaft 62 before referred to. By means of the structure just described, the suction head of the hinge carrier is swung at the proper time from hinge receiving position at the magazine, down past the adhesive applying roller (as indicated in the upper 125 130 135 140 145 150 155 160 165 170 175 180 185 190 195 200 205 210 215 220 225 230 235 240 245 250 255 260 265 270 275 280 285 290 295 300 305 310 315 320 325 330 335 340 broken lines of Fig. 4), to assembling or hinge applying position (as indicated by the lower broken lines in the same figure).

The suction head 87, however, is given a movement toward and away from a carton in the assembling position, and this is accomplished by reciprocating the tube 88. To this end, the tube 88, at its end opposite the suction head 87, carries a head 101 provided with a cam bowl 102 which tracks in a cam groove 103 formed in an arm 104 fast on one end of a short shaft 105 journaled in a bracket 106 rising from the bed plate 19 before referred to. Clamped to the other end of the shaft 105 is an arm 107, the free end of which is connected to one end of a yieldable connecting rod 108 of well known construction and operation, the other end of this connecting rod being pivoted at 109 to a cam lever 110 fulcrumed at 111 to the bracket 98 before referred to. The cam lever 110 carries a cam bowl 112 tracking in a groove in one side of the cam 100 before referred to. By means of the structure just described, the suction hinge carrier head 87 is given a slight movement toward the lowermost hinge in the stack in the magazine when the bracket 91 is in the position shown in Fig. 4. Suction being on, the lowermost hinge in the stack adheres to the carrier which then retreats slightly to pull the adhering hinge from the stack. The hinge carrier then swings down past the adhesive applying mechanism which rolls adhesive upon the exposed surface of the hinge as the carrier moves by the applying roller 77. Then when the hinge carrier has reached the position shown by the lowermost broken lines in Fig. 4, the suction head is given a slight outward movement to press the hinge bearing the adhesive against the side of the carton lid and against the side of the carton body adjacent thereto to cause said hinge to stick to both the body and the lid. Then the suction is cut off by mechanism to be presently described, so that when the suction head again retreats it will not pull the hinge off of the carton. The mechanism for controlling the suction includes a valve casing 113 held on the tube 88 by means of nuts 114. The valve casing is provided with a valve chamber 115, and in this chamber is located a valve 116. This valve is provided with a stem 117 carrying at its upper end a pinion 118 which is in mesh with a sector 119 fulcrumed on a stud 120, the latter being fast in a boss 121 formed on the casing 113 before referred to. As the swinging bracket 91 approaches one end of its movement, the sector 119 comes in contact with an adjustable stop 122 carried by the bracket 93 before referred to. As the bracket 91 approaches the other end of its movement, the sector comes in contact with a similar adjustable stop 123 mounted

on a bracket 124 bolted to the top of the bracket 93 before referred to. By this mechanism the valve is thrown from open to closed position at one end of the path of movement of the bracket 91, and from closed to open position at the other. Suction is established within the tube 88 and hinge carrier head 87 through the agency of a hose 125 connected with a suitable suction producing mechanism, not shown but of well known construction and operation.

A trip mechanism is provided for the purpose of preventing the application of adhesive to the suction head of the hinge carrier in the event that no hinge is lying thereon. This trip mechanism is vacuum controlled. To this end a hose 126 is provided, one end of this hose being in communication with one end of the valve chamber 115, and the other with the interior of a vacuum chamber 127, one side of which is covered by a flexible diaphragm 128, the diaphragm being mounted on one end of a short arm 129 fast on a short shaft 130 journaled in a bracket 131 in which the vacuum chamber 127 is formed. The shaft 130 also carries a trip arm 132. This arm is normally pulled downwardly by a tension spring 133 connecting it with a post 134 fast in the side of the bed plate 19 before referred to. When a hinge is in proper position on the suction head 87, a partial vacuum is created, not only in the tube 88 but in the vacuum chamber 127. In this event, the atmospheric pressure acting on the diaphragm 128 depresses the latter, and this results in lifting the trip arm 132 against the resistance of the spring 133. When, however, there is no hinge on the suction head 87, the interior of the tube 88 will be open to the atmosphere and a vacuum will not be produced in the vacuum chamber 127; and in that event, the trip arm will remain where it is. By this means the swinging movement of the cam arm 104 and the longitudinal movement of the tube 88 will be greater or less in accordance with the position of the trip arm 132 in or out of the path of movement of the arm 104, it being recalled that the connecting rod 108—which operates the arm 104—is of a yielding character; so that, although the movement of the cam lever 110 is always the same, the movement of the cam arm 104 is dependent upon the position of the trip arm 132.

As soon as a hinge has been applied to the exterior of a carton, the latter moves along toward a position where it is opened; and while moving toward that position, the hinge is subjected to pressure and to heat to cause it to become firmly attached to the carton body and lid before the carton is opened. As shown, the pressure device includes a series of brushes 135, 136 and 137 rotating on vertical axes alongside the pathway for the

carton. For the purpose of driving these brushes, there is provided a short shaft 138 driven by means of a sprocket chain 139 from the shaft 85 before referred to. The 5 shaft 138 carries a bevel gear 140 which drives a bevel gear 141 on the lower end of the spindle which carries the rotating brush 137. The spindle of the brush 137 carries a gear 142 which meshes with a pinion 143 10 on the spindle of the brush 136. The pinion 143 meshes with and drives a gear 144 on the spindle of the brush 135. By this means two of the brushes are driven in one direction, and the other in the opposite direction. 15

To permit the leading edge of a hinge on an advancing carton to pass beyond the point where the brush 135 operates, the latter is movable toward and away from the 20 pathway. Just before a carton reaches the brush 135, the latter swings out of the way and remains out of the way until the leading edge of the hinge on the carton has reached a point between the brushes 135 and 136, 25 then the brush 135 swings back on to the hinge, and the two brushes 135 and 136, one rotating in each direction, coact to smooth and press the hinge in place on the carton body and lid. The mechanism by means of 30 which the brush 135 is moved in and out of operative position is as follows: The spindle of the brush 135 is mounted in a swinging frame 145 which is fulcrumed on the axis of the brush 136. A connecting rod 146 connects the swinging frame 145 with the upper arm of a lever 147 projecting upwardly through a suitable aperture in the bed plate 19 and fulcrumed at 148 below said bed plate. 35 The other end of the lever 147 carries a cam bowl 149 tracking on a cam 150 fast on the shaft 85 before referred to. The cam bowl 149 is held against the cam 150 by the action of a tension spring 151 of well known construction and operation.

40 As soon as an advancing carton has passed the brushes just described, it comes within the range of action of an electric heating device 152, the operating surface of which contacts with the hinge already applied to the 45 carton body and lid and operates in a well known manner to dry the glue.

After the exterior hinge has been thus applied to the carton and lid, the carton comes to rest in position to be opened in order that 50 an interior hinge may be applied and in order to permit final inspection of its contents. As shown, the carton opening mechanism includes a latch 153 fast on a short shaft 154 journaled in suitable bearings 155, 55 156 formed on the end of an inverted U-shaped arm 157. This arm is fulcrumed on a short shaft 158 journaled in a bearing 159 supported by the bed plate 19 before referred to. Pivoted to the upper part of the

60 arm 157 at 160 is one end of a connecting rod 161, the other end of which is connected to a cam lever 162 fulcrumed at 163 on a stud carried by a bracket 164 depending from the bed plate 19 before referred to. The lower 65 end of the cam lever 162 carries a cam bowl 165 tracking in a suitable groove in a cam 70 166 fast on the shaft 62 before referred to.

By means of the structure just described, 75 the latch at the proper time engages the lid on the side of the carton opposite the hinge, lifts it, and throws the lid back to open position. Then, after the then open carton has been moved out of the way, the arm carrying the latch swings back to engage the lid of an oncoming carton and open it in the 80 same way.

For the purpose of holding the carton firmly while the lid is being opened, mechanism for clamping the carton body is provided and, as shown, this includes a bar 167 85 against which the hinge side of the carton rests. It further includes a clamp 168 normally occupying the position shown in Fig. 8. This clamp is formed in the end of an arm fast on a short shaft 169 journaled in a bracket 170 screwed to the top of the bed plate 19. Upon the other end of the shaft 169 is fixed a cam arm 171 which is engaged by a cam bowl 172 on the arm 157 when the parts are in the position shown in Fig. 8. 90 A torsion spring 173 coiled around the shaft 169 serves to cause the clamp 168 to swing into engagement with a carton and hold it as soon as the arm 157 moves upwardly and the cam bowl 173 permits the lever 171 to 95 swing in.

From carton opening position, the carton is forwarded to a position where a hinge is applied interiorly. Means employed for this purpose is a duplicate in all essential particulars with that used for applying a hinge exteriorly, and since a description of one answers for a description of the other, the description of the second mechanism of this character is omitted in the interest of brevity and clearness. 100

After an interior hinge has been applied to the carton, the latter is then advanced to a position where it comes within the range of action of a mechanism for pressing the adhesive hinge hard against the inside of the lid. This pressing mechanism consists of a flat plate 174 mounted on a short shaft 175 journaled in bearings in the ends of overhanging arms 176-176 bolted to the machine frame. The shaft 175 projects beyond one of the bearings 176, and upon its projecting end it carries an arm 177. The free end of this arm carries a roller 178 operating against the face of an upright lever 179. This lever is fast on a shaft 180 which runs along the machine just above the bed plate 19, to a position at the left of the opening 110 115 120 125

mechanism. Upon its extreme end it carries a sector gear 181 which is in mesh with a gear 182 on the shaft 158 before referred to. It will be recalled that this shaft 158 is operated by the cam lever 162. When this occurs, the gear 182 will operate the sector gear 181, which in turn will operate the shaft 180. The roller 178 is held against the lever 179 by the action of a tension spring 183.

From the position where the inner hinge is pressed against the lid, the carton is advanced into the range of action of lid closing mechanism. As the carton is advanced 15 with its lid open, the lid slides along a track 184 and off of that on to a shorter track 185, mounted on a bracket 186, bolted to the machine frame. The lid closing mechanism includes an arm 187 having a T-head 188 23 and a hub 189, loose on the shaft 180 before referred to. This hub has a step connection with a collar 190 fast on the shaft 180 before referred to, so that its movement in one direction will be positive. Its movement 25 in the other direction is controlled by means of a torsion spring 191 coiled around the shaft 190 and engaging the hub 189 and the hub of the arm 179. When the shaft 180 is rocked by mechanism heretofore described, 30 the arm 187, which normally rests behind and below the track 185, moves upward to engage the lid, and then over to throw it over on to the top of the carton body.

From the position of carton closure, the 35 cartons are successively ejected from the machine, preferably directly into a wrapping machine which automatically wraps the finished carton.

It will of course be understood that the 40 second or internal hinge applying mechanism is not always necessarily in use.

In view of the foregoing, a detailed description of the operation of the device is believed to be unnecessary and is therefore 45 omitted in the interest of brevity.

What is claimed is:

1. A machine for pasting on a hinge to both the lid and body of a carton in which the lid of the carton is offset from the body, 50 said machine comprising means for supporting the carton with its lid on, a source of hinge supply, and automatic means for withdrawing a hinge from its source of supply and applying it to the offset lid and means 55 for applying the hinge to the body portion of the carton.

2. A machine for pasting on hinges between an offset lid and the body of a carton comprising means for supporting the carton 60 with its lid on and continuously holding it in said position while passing it through the machine, a source of hinge supply, means for withdrawing a hinge from the hinge supply and pasting it to the offset lid, and means for

subsequently pasting the hinge to the body 65 of the carton.

3. A machine for pasting on carton lid hinges in which the lid is offset from the body of the carton comprising means for supporting the cartons with their lids on, 70 selective means for moving the carton lid side up through the machine, a hinge supply, means for withdrawing a hinge from the supply, applying the paste thereto and attaching the hinge first to the offset lid and 75 means for subsequently attaching the hinge to the body portion of the carton.

4. A carton hinging machine comprising means for supporting cartons right side up 80 as they pass through the machine, a source of carton supply, a source of hinge supply, and means for successively assembling in said supporting means cartons and hinges drawn from said sources, said assembling 85 means including mechanism for applying hinges to the interior of the lids and to the cartons.

5. A carton hinging machine comprising means for supporting cartons right side up 90 as they pass through the machine, a source of carton supply, a source of hinge supply, and means for successively assembling in said supporting means cartons and hinges drawn from said sources, said assembling 95 means including a hinge carrier, and operative connections for causing said carrier to apply hinges to the interior of the lids and to the cartons.

6. A machine for pasting on a hinge both 100 to a lid and body of a carton wherein its lid is offset from its body, comprising a source of supply for supporting the carton with its lid on and top side up, means for moving a carton from its source of supply through the machine with its top side up, a hinge 105 source with means for withdrawing a hinge from said hinge source and applying paste thereto over one side thereof and attaching the upper portion of the hinge to the offset lid, and means for subsequently attaching the lower portion of the hinge to the body 110 of the carton.

7. A machine for pasting on a hinge both 115 to a lid and body of a carton wherein the lid of the carton is offset from its body comprising means to support the cartons one above the other, means for moving the bottom carton from the support to assembly position with its top side up, a hinge source and means to withdraw a hinge from its 120 source and apply it to the carton offset lid only, means for moving the carton while retaining it in its top side up position, and means for pasting the lower side of the hinge to the body portion.

8. A machine for hinging a lid to the body of a carton wherein the lid is offset 125 from the body of the carton, comprising

- means for supporting cartons top side up and one above the other, a carton selecting and moving mechanism including a carton conveying chain provided with carton engaging lugs for forwarding the cartons from 5 said support to assembling position, a source of hinge supply and means for withdrawing a hinge from said source of supply and pasting it to the lid of the carton while it is held 10 in its top side up position and means for subsequently attaching the hinge to the body of the carton after said chain has conveyed the carton to a new position. 15 9. A machine for hinging offset lids to the bodies of cartons, comprising means for supporting the cartons top side up, means for selecting and moving the carton intermittently to a hinge applying position, a source of hinge supply, means for withdrawing 20 a hinge, applying paste thereto, and applying a hinge to the lid of the carton after one movement of the carton to hinge assembling position, and means for attaching the hinge to the body of the carton after 25 another intermittent movement of the carton. 10. A machine for hinging lids to the body of cartons, comprising means for supporting the cartons one upon the other, means for intermittently moving the bottom 30 carton comprising a chain with carton engaging lugs movable intermittently along a horizontal pathway to bring the carton to hinge applying positions, a source of hinge 35 supply, means for withdrawing a hinge by a movement thereof at right angles to the plane of the hinge, and applying glue to the hinge and the hinge to the lid only of the carton, and means for subsequently applying 40 the hinge to the body of the carton after a movement of the carton from its first hinge applying position. 11. A carton hinging machine for hinging the lid to the body of the carton comprising a source of carton supply, a source 45 of hinge supply and means for moving step by step, the cartons from the source of supply to the hinge supply, means for withdrawing a hinge from the source of hinge 50 supply, applying paste thereto over one side thereof and attaching the hinge to the lid only of the carton, and a series of rollers stationed along the carton path and adapted to attach the hinge to the body of the carton. 55 12. A carton hinging machine comprising a source of carton supply, a source of hinge supply, an adhesive source of supply, and means for successively assembling cartons and hinges drawn from their respective 60 sources, said assembling means including a suction hinge carrier operative to withdraw a hinge from the hinge supply and move the same to adhesive supply position, means cooperative with the suction hinge carrier to 65 apply adhesive to the hinge comprising an adhesive applying roller operative on a fixed pivot over the surface of which the hinge is moved by said carrier, said suction hinge carrier being then movable to apply the hinge to the carton. 70 13. A machine for pasting on a hinge to both the lid and body of a carton in which the lid of the carton is offset from the body, said machine comprising means for supporting the carton with its lid on, a source of hinge supply, an automatic means for withdrawing a hinge from its source of supply and applying it to the offset lid, said means including a suction hinge carton, and means for applying the hinge to the body portion 80 of the carton. 14. A carton hinging machine comprising a source of carton supply, a source of hinge supply and an adhesive source of supply, means for successively assembling cartons and hinges drawn from said sources, said assembling means including a suction hinge carrier movable successively to withdraw a hinge and move it to adhesive applying position, adhesive applying means cooperative therewith to apply adhesive to the hinge, said hinge carrier being thereupon automatically moved to apply the hinge to the carton lid and means for applying the hinge to the 85 carton body. 15. A carton lid hinging machine comprising a source of carton supply, a source of hinge supply, means for successively assembling cartons and hinges drawn from said sources, said means including a device for withdrawing the hinges from the hinge source of supply and applying the hinge to the carton lid, and a series of rotary brushes for subsequently pressing the hinges against the carton body. 90 16. A carton hinging machine comprising a carton support, a source of hinge supply and a swinging tube for extracting a hinge from the hinge supply, said tube being movable against the source of hinge supply and away from it, an adhesive applying roller revoluble on a fixed pivot and against which the hinge is moved by said tube, said tube being also movable sidewise to bring a hinge in position to cooperate with the adhesive supplying means, said tube being also movable sidewise in the same direction to bring the hinge opposite the carton and then movable toward the carton to apply the hinge 95 to the carton. 17. A carton lid hinging machine comprising a source of carton supply, means for successively assembling cartons and hinges drawn from said sources, means for applying the hinge to the outside of the lid and carton, and means for applying hinges to the inside of the lid and to the carton. 100 18. A carton hinging machine comprising means for supporting cartons right side up as they pass through the machine, a source 105 110 115 120 125 130

of carton supply, a source of hinge supply, and means for successively assembling in said supporting means cartons and hinges drawn from said sources, said assembling 5 means including a movable suction hinge carrier, an adhesive fountain, and a roller receiving adhesive from said fountain and having a surface speed equal to that of the movable carrier to transfer adhesive to a 10 hinge on said carrier.

19. A carton hinging machine comprising a source of carton supply, a source of hinge supply, and means for successively assembling the cartons and hinges drawn from 15 said sources, means for automatically applying hinges on the exterior of the carton, automatic means for opening the carton and automatic means for applying hinges on the interior of the carton lid and to the carton.

20. A machine for pasting on a hinge of both the lid and body of a carton in which the lid of the carton is offset from said body, said machine comprising means for pasting the hinges on the lid, means for pasting the 25 hinge to the body of the carton, means for raising the lid of the carton, and means for pasting the hinge to the inside of the lid and to the exterior of the carton.

21. A carton hinging machine comprising 30 means for supporting cartons right side up as they pass through the machine, a source of carton supply, a source of hinge supply, and means for successively assembling in said supporting means cartons and hinges 35 drawn from said sources, said assembling means including a series of brushes, and means for rotating said brushes in different directions for pressing hinges against the cartons.

40 22. A carton hinging machine comprising means for supporting cartons right side up as they pass through the machine, a source of carton supply, a source of hinge supply, and means for successively assembling in 45 said supporting means cartons and hinges drawn from said sources, said assembling means including mechanism for opening each carton after a hinge has been applied to its exterior to permit final inspection of its 50 contents.

23. A carton hinging machine comprising means for supporting cartons right side up as they pass through the machine, a source 55 of carton supply, a source of hinge supply, and means for successively assembling in said supporting means cartons and hinges drawn from said sources, said assembling means including a latch and operative connections for opening each carton after a hinge has been applied to its exterior.

24. A carton hinging machine comprising 60 means for supporting cartons right side up as they pass through the machine, a source of carton supply, a source of hinge supply, and means for successively assembling in 65 said supporting means cartons and hinges drawn from said sources, said assembling

said supporting means cartons and hinges drawn from said sources, said assembling means including a latch and cam-actuated connections for opening each carton after a hinge has been applied to its exterior.

25. A carton hinging machine comprising 70 means for supporting cartons right side up as they pass through the machine, a source of carton supply, a source of hinge supply, and means for successively assembling in 75 said supporting means cartons and hinges drawn from said sources, said assembling means including mechanism for closing each carton after a hinge has been applied to the interior of the lid and to the carton.

26. A carton hinging machine comprising 80 means for supporting cartons right side up as they pass through the machine, a source of carton supply, a source of hinge supply, and means for successively assembling in 85 said supporting means cartons and hinges drawn from said sources, said assembling means including an arm engaging the lid of each carton after a hinge has been applied to its interior, and operative connections acting to swing said arm to close the carton.

27. A carton hinging machine comprising 90 means for supporting cartons right side up as they pass through the machine, a source of carton supply, a source of hinge supply, and means for successively assembling in 95 said supporting means cartons and hinges drawn from said sources, said assembling means including an arm engaging the lid of each carton after a hinge has been applied 100 to its interior, and cam-actuated operative connections acting to swing said arm to close the carton.

28. A carton hinging machine comprising 105 means for supporting cartons right side up as they pass through the machine, a source of carton supply, a source of hinge supply, and means for successively assembling in 110 said supporting means cartons and hinges drawn from said sources, said assembling means including mechanism for holding the body of each carton while its lid is being opened and means for opening the lid.

29. A carton hinging machine comprising 115 means for supporting cartons right side up as they pass through the machine, a source of carton supply, a source of hinge supply, and means for successively assembling in 120 said supporting means cartons and hinges drawn from said sources, said assembling means including a clamping device for holding the body of each carton while its lid is being opened and means for opening the lid.

30. A carton hinging machine comprising 125 means for supporting cartons right side up as they pass through the machine, a source of carton supply, a source of hinge supply, and means for successively assembling in 130 said supporting means cartons and hinges drawn from said sources, said assembling

means including carton forwarding mechanism, dual hinge forwarding mechanism one for exterior hinges and one for interior hinges, dual adhesive applying mechanism one coating with each hinge forwarding mechanism, and independent mechanisms for pressing exterior hinges and interior hinges against the cartons.

31. A carton hinging machine comprising
10 means for supporting cartons right side up
as they pass through the machine, a source of carton supply, a source of hinge supply,
and means for successively assembling in
said supporting means cartons and hinges
15 drawn from said sources, said assembling

means including carton forwarding mechanism, dual hinge forwarding mechanism one for exterior hinges and one for interior hinges, dual adhesive applying mechanism one coating with each hinge forwarding mechanism, independent mechanisms for pressing exterior hinges and interior hinges against the cartons, and independent mechanisms for opening the cartons
20 after exterior hinges have been applied thereto and for closing the cartons after interior hinges have been applied thereto.

In testimony whereof, I have signed my name to this specification.

OTTO SCHWENCK.
